[57] **ABSTRACT**

Apparatus for making hanging file folders of the type having a strip of metal along opposite sides and by means of which the folder can be hung on two parallel hangers. The apparatus includes means for transferring a V-shaped rod from a stack and to a swingable transfer arm, the swingable transfer arm then transferring the rod to the edge of the file blank for being clamped therealong. The apparatus also includes pressure pads for holding the stack of rods and releasing the lowermost rod at the appropriate time so that it can be picked up by the pick-up arms.

A machine for forming file folder blanks from a web, and automatically applying a rod on each of opposite sides of said blanks, said machine employing an apparatus of the above type at each side of the path of movement of said blanks.

MACHINE FOR MAKING HANGING FILE FOLDERS

BACKGROUND OF THE INVENTION

This invention pertains to means for automatically applying a metal rod from a stack of rods and conveying it to a file folder blank for application to each of opposite sides thereto. Heretofore, this process has been carried out largely by hand.

SUMMARY OF THE INVENTION

The present invention provides a machine and apparatus therefor, for automatically applying a rod to each of two opposite sides of a file folder blank which has been formed from paperboard or the like. Such an apparatus is located on each side of the path of movement of the blank, and the apparatus removes the lowermost rod from a supply stack of rods and swings the rod into position along each side of the blank where a die can then secure the rods to the blank. The apparatus also includes pressure pad means for holding the supply stack of rods and releasing the lowermost rod in each stack so that it can be picked up by pick-up arm means and delivered to timed transfer arm means for engagement with the edge of the blank.

These and other objects and advantages of the present invention will appear hereinafter as this disclosure progresses, reference being had to the accompanying drawings.

BRIEF DESCRIPTION OF THE DRAWINGS

FIG. 1 is a schematic view of the rod advancing mechanism and associated parts of a machine for producing a hanging file;

FIG. 2 is a perspective view of the left hand rod advancing mechanism that is located on the far side of FIG. 1;

FIG. 3 is a development view of the rod advancing mechanism;

FIG. 4 is a cross sectional view taken on line 4—4 in FIG. 3, showing the rod latch and transfer arms on their respective rocker shafts, with the addition of a clamping die;

FIG. 5 is a cross section similar to FIG. 4 taken on line 5—5 in FIG. 3 showing the inside cam and follower that actuates the pressure pad to release a rod into the rod latch, starting the cycle;

FIG. 5A is a view of the pressure pad removed from its pivotal connection in FIG. 5;

FIG. 6 is a view of the stationary cam and rod latch cam follower starting its downward stroke after being loaded;

FIG. 6A is a view of the rod latch, removed from its pivotal connection in FIG. 6 and shown in an upright position;

FIG. 7 is a view similar to FIG. 6 in an advance condition with the rod latch open and the transfer arm picking up a rod; and

FIG. 8 is a view of the transfer arm and associated parts, finally positioning the rod on the hanging file material prior to clamping.

DESCRIPTION OF A PREFERRED EMBODIMENT

General

As shown in FIG. 1, a roll of paperboard P or the like is fed by conventional feed rolls 1 to a cutter bar 2 operated from crankshaft 2a, and the bar 2 cuts the web into predetermined lengths that constitute blanks B. The blanks then are fed by the rolls 3 between apparatus A and A1 located on each side of the blank. A scoring roll 4, driven by the web itself, acts to score a longitudinal centerline in the web so that the blank can ultimately be folded.

The apparatus A and A1, to be described in detail, act to apply a metal, V-shaped rod R to opposite sides of the blank and then the completed blank passes from the apparatus on rollers 5, where the finished blank can be subsequently handled.

The apparatus A is shown in perspective in FIG. 2 and as apparatus A and A1 are similar, only one of them will be described hereinafter in detail.

Rod stacking means 6 are provided at each side of the blank and adjacent their respective apparatus, and these stacking means include a pair of vertically arranged channel members 7, in which the ends of the rods are held so that the rods can be stacked in a vertical direction with their open sides facing upwardly, as clearly shown in FIGS. 4 and 5.

MAIN FRAME AND DIE

The main frame of the machine includes a stationary lower member 8 (FIGS. 4, 5 and 8) which has a horizontally disposed die 8a secured thereto. A vertically shiftable frame member 9 and its die 9a are reciprocated in a vertical direction by the crankshaft 9b. Die 9a complements die member 8a and acts therewith to clamp the rod R along the edge of the blank B after the rod has been delivered from the supply stack into engagement with the edge of the blank, as follows:

The apparatus A includes a steel fabricated frame 10 including bracketed attaching portions 10a (FIGS. 2, 4, 5 and 8) by means of which the apparatus is secured to the main machine frame 8 by the bolt means 11. A series of four shafts 12, 20, 24 and 40 are rotatably journaled in suitable anti-friction bearings in the frame member 10 as follows.

POWER INPUT MEANS

A power input shaft 12 receives power through its gear 13 from a power source (not shown) and is continuously driven. A gear 14 is fixed by key 15 to shaft 12. Also secured to shaft 12 are a pair of cams 16 and 17 having interior cam tracks 16a and 17a, respectively. Another cam 18 is also fixed to shaft 12 and these cams will be referred to hereinafter.

Another shaft 20 has a gear 21 fixed to its outer end which is in constant mesh with gear 14 and consequently is also continuously driven. A cam 22 is fixed to shaft 20 for the purpose of oscillating the transfer shaft 24 journaled in the frame 10.

TRANSFER MEANS

The transfer shaft 24 has a pair of transfer arms 25 and 26 fixed thereto at spaced locations therealong and

these transfer arms have an extending portion 28 (FIG. 8). These extending portions 28 cooperate with the vertically disposed rod guide members 29 which are stationary and fixed to bracket members 10a. It will be noted that the upper surfaces 29a of the rod guide members are curved and cooperate with the extending portions 28 of the transfer arms in holding and guiding the rods R as they are delivered from the pickup arms (to be described), and into engagement with the blank B. The one transfer arm 26 has a cam follower 30 fixed therewith on stub shaft 31, and this cam follower 30 follows the cam 22 which is fixed to shaft 20. Thus, the continuously rotating shaft 20 and its cam 22 act to oscillate the transfer shaft 24 and its pair of transfer arms 25 and 26. This oscillation is from the rearward position shown in FIGS. 4 and 5 to the fully extended and lower position (shown by the broken line in FIG. 8) where the rod R is pushed into embracing engagement with the blank B.

An air cylinder 34 (FIG. 4) connected to the frame of the apparatus and also by pin 34a in an arm 35 fixed to shaft 24. The cylinder 34 is continuously biased to hold the cam follower 30 against the cam 22 fixed on shaft 20.

ROD PICK-UP MEANS

The fourth shaft 40 constitutes a pick-up shaft and has a pair of pick-up arms 41 and 42 fixed thereto for oscillation therewith. The arms 41 and 42 oscillate between an upper position shown in FIG. 4, where they act to receive the rod R from the stacking means 6, and a lowermost position (FIG. 7) where the transfer arms 25 and 26 act to remove the rod from these transfer arms 41 and 42. More specifically, the arms 41 and 42 have a generally upwardly extending V-shaped recess 41a and 42a, respectively, in which the lowermost rod R in the supply stack is embraced.

Releasable latch means are provided for each of the transfer arms 41 and 42 to positively hold the rod R in the V-shaped recess 41a and 42a until the rod is transferred to the transfer arms 25 and 26. These latch means are as follows.

A hook-like latch 46 (FIG. 5) is pivotally mounted at 47 on each of the arms 41 and 42. These latches each have a cam follower roller 48 at their other end which rides on a stationary cam 49. Cams 49 are held stationary by their brackets 49a. Cam 49 has a recessed surface 50 and a raised surface 51. When roller 48 is on the recessed surface 50 (FIG. 5) the other, hook-end 46a of the latch 46 extends over the edge of lowered rod R (FIG. 6) and securely holds the rod in the pick-up arms 41 and 42. Then, when shaft 40 rotates, roller 48 rides up on the raised portion 51 of the stationary cam 49, thereby causing the hook-end of the latch to withdraw from the rod against the bias of spring 53, thereby releasing the rod (FIG. 7) for transfer by arms 25 and 26.

An air cylinder 55 is connected between the frame 10 and the end of arm 42 which is opposite to the end of arm 42 having the V-shaped recess 42a. A cam follower roller 56 (FIGS. 4 and 6) is also mounted on arm 42 and rides on cam 18. Thus, rotation of shaft 12 and its cam 18 causes oscillation of arms 41 and 42, as above described. Cylinder 55 biases the follower roller 56 against the cam 18.

5 Pressure pad means 43 and 44 are also connected with shaft 40 and as shown in FIG. 4 act to bear against that rod of the stack which is immediately above the lowermost rod which has been latched and is ready to be moved away. These pressure pads hold the remaining rods in position in the stack and prevent them from falling downwardly until the appropriate time when the lowermost rod is picked up by the pick-up arms 41 and 42. More specifically, the pressure pad means 43 and 44 include an arm 43a pivoted at 45 (FIG. 5) to a hub 45a fixed on shaft 40, and roller 45b is also carried on the hub 45a. Roller 45b rides in the cam track 16a. Thereby, rotation of the cam 16 causes the pressure pad means 43 and 44 to periodically bear against and hold the stack of rods, and then periodically release the lowermost rod.

RESUME

20 Thus, the pick-up arms 41 and 42 when in the position shown in FIG. 4, engage the lowermost rod R and the pressure pads means 43 and 44 at that time are holding this lowermost rod in the stacked position. As the shaft 40 rotates, the roller 45b drops in the recessed portion 16b of cam 16, thereby causing the pressure pad means to be removed momentarily from the lowermost rod. Rotation of shaft 40 causes the transfer arms to swing downwardly carrying with it the lowermost rod, the pressure pad then again bearing against the subsequent rod in the stack to hold the stack in place.

25 The latches 46 are also released, from the rod being transferred, when shaft 40 has rotated sufficiently to place the rod in transfer arms 25 and 26.

30 After the transfer arms have placed the rods in embracing position along opposite edges of the blank, the die members 9a descend to clamp the rod shut and into binding engagement with the edges of the file folder blank thus completing the file folder.

35 I claim:

1. A machine for automatically applying hanger rods to two opposite sides of a file folder blank, said machine comprising, means for advancing a web of paperboard or the like along a predetermined path, cutter means for severing said web into predetermined length blanks, scoring means for scoring said blanks, die means mounted on the machine and located along opposite edges of said blank as they move along said predetermined path, rod supply means located adjacent each of said die means, and apparatus located at each side of said blank for automatically removing rods from said supply means and applying said rods to each of said opposite edges of said blank, said apparatus comprising; a frame, pick-up means mounted in said frame and swingable between a rod pick-up position adjacent said rod supply means and a transfer position away from said supply means, transfer means mounted in said frame and swingable between (1) said transfer position for receiving a rod from said pick-up means and (2) a rod applying position in which the rod is caused to embrace said edge of said blank, and means mounted in said machine and connected with and for operating said pick-up means and said transfer means in timed relationship with one another; and means for operating said die means for securing said rods to said edges of said blanks.

2. The machine set forth in claim 1 wherein said apparatus includes rod guide means in said frame for cooperation with said transfer means in guiding and transferring said rod from said transfer position to said rod applying position.

3. The machine set forth in claim 1 wherein said pick-up means includes releasable latch means for holding said rod in said pick-up means.

4. The machine set forth in claim 2 wherein said pick-up means includes releasable latch means for holding said rod in said pick-up means.

5. The machine set forth in claim 1 including releasable pressure pad means for abutting against the rods in said supply means to prevent inadvertent release of a rod from said supply means.

6. Apparatus for automatically applying a hanger rod to a file folder blank and comprising; a frame having means for mounting adjacent the edge of a movable blank and also adjacent a rod supply means for holding rods to be secured to said blank, pick-up means mounted in said frame and swingable between a rod pick-up position adjacent said rod supply means and a transfer position away from said rod supply means, transfer means mounted in said frame and swingable between (1) said transfer position for receiving said rod from said pick-up means and (2) a rod applying position in which the rod is caused to embrace said edge of said blank, and means connected with and for operating said pick-up means and said transfer means in timed relationship with one another.

7. The apparatus set forth in claim 6 including rod guide means in said frame for cooperation with said transfer means in guiding and transferring said rod from said transfer position to said rod applying position.

8. The apparatus set forth in claim 6 wherein said pick-up means includes releasable latch means for holding said rod in said pick-up means.

9. The apparatus set forth in claim 7 wherein said pick-up means includes releasable latch means for holding said rod in said pick-up means.

10. The apparatus set forth in claim 6 including releasable pressure pad means for abutting against the rods in said rod supply means to prevent inadvertent release of a rod from said supply means.

11. Apparatus for automatically applying a hanger rod to a file folder blank and comprising; a frame having means for mounting adjacent the edge of a movable blank and also adjacent a rod supply means for holding rods to be secured to said blank, releasable pressure pad means for abutting against the rods in said rod supply means to prevent inadvertent release of a rod from said supply means, pick-up means mounted in said frame and swingable between a rod pick-up position adjacent said rod supply means and a transfer position away from said rod supply means, said pick-up means including releasable latch means for holding said rod in said pick-up means, transfer means mounted in said frame and swingable between (1) said transfer position for receiving said rod from said pick-up means

6 and (2) a rod applying position in which the rod is caused to embrace said edge of said blank, rod guide means in said frame for cooperation with said transfer means in guiding and transferring said rod from said transfer position to said rod applying position, and means connected with and for operating said pick-up means and said transfer means in timed relationship with one another.

12. A machine for automatically applying hanger rods to two opposite sides of a file folder blank, said machine comprising, means for advancing a web of paperboard or the like along a predetermined path, cutter means for severing said web into predetermined length blanks, scoring means for scoring said blanks, die means mounted on said machine and located along opposite edges of said blank as they move along said predetermined path, rod supply means for holding a stack of rods and located adjacent each of said die means, releasable pressure pad means for abutting against the rods in said supply means to prevent inadvertent release of a rod from said supply means, and apparatus located at each side of said blank for automatically removing rods from said supply means and applying said rods to each of said opposite edges of said blank, said apparatus comprising; a frame, pick-up means mounted in said frame and swingable between a rod pick-up position adjacent said rod supply means and a transfer position away from said supply means, said pick-up means including releasable latch means for holding said rod in said pick-up means, transfer means mounted in said frame and swingable between (1) said transfer position for receiving a rod from said pick-up means and (2) a rod applying position in which the rod is caused to embrace said edge of said blank, rod guide means in said frame for cooperation with said transfer means in guiding and transferring said rod from said transfer position to said rod applying position, and means connected with and for operating said pick-up means and said transfer means in timed relationship with one another; and means for operating said die means for securing said rods to said edges of said blanks.

13. A machine for automatically applying hanger rods to two opposite sides of a file folder blank, said machine comprising, means for advancing a web of paperboard or the like along a predetermined path, cutter means for severing said web into predetermined length blanks, scoring means for scoring said blanks, die means mounted on said machine and located along opposite edges of said blank as they move along said predetermined path, rod supply means located adjacent each of said die means and for supporting a stack of rods, and shiftable means located at each side of said blank and engageable with the lowermost rods of said stacks for automatically removing said rods from said supply means and applying said rods to each of said opposite edges of said blank; and means for operating said die means for securing said rods to said edges of said blanks.
